UNITED STATES PATENT OFFICE.

WALTER W. CONNERS, OF CHICAGO, ILLINOIS.

EXPLOSIVE-ENGINE.

1,135,501.

Specification of Letters Patent. Patented Apr. 13, 1915.

Application filed March 9, 1914. Serial No. 823,435.

To all whom it may concern:

Be it known that I, WALTER W. CONNERS, a citizen of the United States, residing at Chicago, in the county of Cook and State of Illinois, have invented certain new and useful Improvements in Explosive-Engines; and I do declare the following to be a full, clear, and exact description of the invention, such as will enable others skilled in the art to which it appertains to make and use the same.

This invention relates to improvements in explosive engines and more particularly to those of the upright type.

The primary object of the invention is to provide an internal combustion engine having a main power piston and a supplemental piston movable toward or away from each other and within the same cylinder, said supplemental piston acting simultaneously to discharge the burnt gases from said cylinder and to draw in a new charge of live gases.

To the above end, it becomes necessary to provide a by-pass from the top of the cylinder to a point nearer the lower end thereof.

A secondary object, therefore, is to provide means for automatically clearing said by-pass of burnt gases.

Another object lies in constructing said means in such a manner as to cause the lower end of said by-pass to be closed upon intake strokes of the supplemental piston.

A still further object is to provide simple and efficient means for controlling the movements of said supplemental piston.

With the above objects in view, the invention resides in certain novel features of construction and combination herein described and claimed and shown in the drawings wherein:

Figure 1 is a vertical longitudinal section through my improved engine, parts being shown in elevation for the sake of clearness, and the pistons being shown in the position which they assume at the moment the gases are to be ignited within the cylinder; Fig. 2 is a sectional view taken at right angles to Fig. 1, showing the same position of the pistons and also the position which the plunger within the by-pass assumes when the remainder of the parts are in this position; Figs. 3 and 4 are views similar to Fig. 2 and show respectively the position of parts at the end of a power stroke and at the end of a combined exhaust and intake stroke

of the supplemental piston; Fig. 5 is a vertical section similar to the figures just described and showing the position of the pistons and the plunger within the by-pass which they assume near the completion of a compression stroke of the power piston; Fig. 6 is an enlarged vertical section through a portion of the cylinder and the by-pass; Fig. 7 is a side elevation of a portion of the cylinder and showing the construction of the controlling means for the supplemental piston; and Fig. 8 is a detail side elevation of the upper portion of the cylinder and the parts mounted thereon.

In the accompanying drawings, I have shown my improved explosive engine as comprising in general, a base 1 which also constitutes a crank case and in which the crank shaft 2 is journaled, a cylinder 3 rising from the upper end of said combined base and crank case, a main power piston 4, a supplemental piston 5 and the hereinafter described mechanism for operating said supplemental piston.

The crank shaft 2 is journaled in suitable bearings in the opposite sides of the combined base and crank case 1 and the crank 6 of said shaft preferably revolves between a pair of upright walls 7 through which the shaft 2 is also journaled and which are suitably shaped at their upper ends to form a circular support for the lower end of the cylinder 3, which is preferably threaded into said support.

Rigidly keyed upon the shaft 2 between the outer wall of the base 1 and one of the upright walls 7, is a spur gear 8 which meshes with a similar gear 9 rigidly keyed upon a crank shaft 10 which has its inner end revolvably mounted in one of the walls 7, while its outer end is rotatably supported in a suitable bearing formed on the upper terminal of an arm 11 which has its lower end 12 journaled around said shaft 2. This arm 11 is suitably supported by means of a bolt 13 which is pivotally secured near the upper end of said arm 11, passes through an opening in said base or crank case, and receives a nut 14, which is swiveled upon the outer face of said crank case in any suitable manner.

The cylinder 3 is provided near its upper end with a by-pass 15 which communicates with said cylinder by a number of ports 16 and is preferably of cylindrical contour for the reception of a plunger 17, which is

pressed normally upward by means of a coil spring 18 which rests against an ear 19 and encircles the stem 20 of said plunger which is slidable through said ear. The operation 5 of the plunger 17 will be hereinafter more clearly set forth. In addition to the ports 16 and the by-pass 15, the cylinder 3 is provided, in its extreme upper end with an intake port 21 which communicates with the 10 interior of a suitable casing 22 in which a spring closed intake valve 23 is mounted for vertical movement. The stem of the valve 23 is provided with upper and lower shoulders 24 and 25, a coil spring 26 pressing normally against the shoulder 24 and against the lower end of the casing 22 to retain the valve 23 in closed position. Directly below the intake port 21 is an exhaust port 27 which communicates with the 20 interior of a casing 28 in which an exhaust valve 29 is mounted for vertical movement, the stem of said valve rising and being provided with upper and lower collars 30 and 31, a coil spring 32 being secured at its 25 opposite ends to the collar 31 and to the upper end of the casing 28, whereby said valve 29 is normally held seated within its casing.

The piston 4 may be of the usual or any 30 desired construction and is connected in a well-known manner to the crank by a piston rod 33. The supplemental piston 5 is of considerably less length than the piston 4 and is clearly shown in the drawings as located 35 above said piston 4 and is carried by the lower end of an upright piston rod 34 which slides loosely through a stuffing box 35, the latter being disposed between the top of the cylinder 3 and the top of a suitable water jacket 36 and operating between 40 a pair of upright guides 37 which are rigidly secured to the top of said water jacket.

Slidable between the guides 37 and upon the piston rod 34 is a cross head 38, the 45 arms 39 of which project laterally and are connected by links 40 with the outer ends of arms 41 which are rigidly secured to the opposite ends of a rock shaft 42, the latter being revolvably mounted in a horizontal 50 position in suitable bearings carried by the water jacket 36. The arms 41 are spaced a suitable distance from said water jacket to prevent contact therewith and one of said arms 41 is pivotally connected by means of 55 a link 43 with the crank 10' of the crank shaft 10 which is driven by the gears 8 and 9 in a manner to appear. As clearly shown in the drawings, one of the arms 41 is spaced a considerable distance from the stems of 60 the intake and exhaust valves 23 and 29 and is also located outside of an upright rod 45 which carries a pair of inwardly extending fingers 46 and 47 which are provided on their inner ends with eyes which slide loosely 65 upon the stems of said valves between the

collars thereon. The rod 45 is provided with upper and lower stops 48 and 49 near its upper end, said end lying in approximately the plane of the upper ends of the guides 37, while its lower portion passes through a suitable opening in the top of the crank case 1 and is connected to an eccentric band 50 within which revolves an eccentric 51 which is keyed upon the shaft 2 on the opposite side of the engine from 70 the gear 8.

Co-acting with the eccentric 51 and the rod 45, for the purpose of regulating the movement of the cross head 38 and the piston rod 34 and therefore, the movements of 80 the supplemental piston 5, I employ mechanism now to be described. Pivoted mounted at 52 upon a suitable supporting arm which may well be carried by one of the guides 37, is a bell crank lever 53 which has 85 one of its arms lying in a horizontal plane and provided with an eye 54 through which the portion of the rod 42 between the stops 48 and 49, loosely slides while its other arm stands substantially upright and is provided with a horizontal extension 55' which is pivotally connected at 55 to a rod 56, the lower end of which is pivoted to the upper end of the water jacket 36. Pivoted 90 mounted upon the pivot 55 connecting the arm 54 with the rod 56, is a substantially horizontal link 57 which is pivoted to the upper end of a hook 58, which, as shown (see Fig. 7) is fulcrumed intermediate its 95 ends upon a suitable bracket or arm. Slid- 100 able upon the rod 56 is an eye 59 which is formed on the upper end of an arm 60 which rises from a hook 61 which is pivoted at its lower end to the cross head 38, as clearly shown at 62. The bills 58' and 61' 105 of the hooks 58 and 61 respectively are adapted to engage notches 63 and 64 formed in one side of the piston rod 34 above the cross head 38. By this construction and 110 mounting of the hooks 58 and 61 and their operating mechanism, when the rod 45 is raised or lowered by the eccentric 51, the shoulders of said rod will contact with the eye 54 and will thus operate said hooks in a 115 manner to be more clearly set forth.

With the parts as above described, the 120 operation of the device is as follows: Assuming that a compressed charge of gas is within the cylinder 3 between the pistons 4 and 5 and that said pistons assume the positions shown in Fig. 2: the spark is now fired by a suitable spark plug P which may well project into the by-pass 15 and the compressed gases within the cylinder will be 125 ignited. When the parts stand in this position, the bill 58' of the hook 58 is engaged with the notch 63 in the piston rod 34 of the supplemental piston 5 and thus prevents said supplemental piston from moving with 130 in the cylinder 3. The ignition of the gases

above the piston 4 will of course cause said piston to descend and this movement will impart a rotary motion to the crank shaft 2 of the engine and will, through the action 5 of the gears 8 and 9, the link 43, the arms 41, and the links 40, move the cross head 38 upwardly. By the time said cross head has moved to its uppermost position and the piston 4 has turned the crank 6 of the shaft 10 2 to a point approximately 10 degrees in advance of its lower dead center, the eccentric 51 has raised the rod 45 and has caused the stop 49 to contact with the under side of the eye 54 and thus rocked the bell crank 15 lever 53 in such a manner as to disengage the bill of the hook 58 from the notch 63 in the piston rod 34 and to engage the bill of the hook 61 with the notch 64 in said piston rod. The upward movement of the rod 20 45 has, simultaneously with the shifting of the hooks 58 and 61, caused the finger 47 to contact with the shoulder 30 on the stem of the valve 29 and thus said valve has been opened and the exhaust port 27 is in communication with the open air. The momentum imparted to the shaft 2 and a suitable fly wheel F will now continue to rotate the gear 9 and the crank 10' driven thereby is moved downwardly from the raised position 30 which it now assumes. This downward movement on the part of the crank 10', will, through the hereinbefore described connections, pull downwardly upon the arms 39 of the cross head 38 which is at this time 35 connected with the piston rod 34 by the hook 61, which rod will now be pulled downwardly and will, therefore, force the supplemental piston 5 toward the piston 4, which by this time is traveling upwardly. 40 The two pistons in thus coming together, will effectually drive all exhaust gases out of the cylinder and the descent of the piston 5 will also draw in a new charge of gas through the inlet valve 23. 45 It may here be stated that when the gas formerly stood compressed between the two pistons, the plunger 19 was compressed against its spring 18, but when said gas was ignited, and the piston 4 traveled downwardly, said plunger was forced upwardly by its spring and thus drove all exhaust gases from the by-pass 15 into the top of the cylinder 3 from which they will be expelled by the descent of the piston 5. The 50 ascent of the plunger 17 not only expels the exhaust gases from the by-pass 15, but it closes the various ports 16 which communicate through said by-pass into the interior of the cylinder 3 and thus prevents the descent of the piston 5 from drawing any of the burnt gases into the top of the cylinder and thus causing said supplemental piston 5 to draw nothing but fresh gas into the upper end of said cylinder. As the piston 4 is 55 now raised through the action of the fly wheel F, the piston 5, traveling much faster than said piston 4, reaches the top of the cylinder and as it assumes this position, forces the charge of fresh gas out certain of the ports 16, through the by-pass 15 and 70 into the space between said pistons 4 and 5, this movement on the part of the fresh gas being made possible by the fact that the gas in being compressed, forces the plunger 17 again downwardly and uncovers said 75 ports 16. By the time the piston 5 has reached the top of the cylinder 3, the hook 61 is again disengaged from the notch 64 and the hook 58 is again engaged with its notch 63, this being done by the lowering of 80 the rod 45 by the eccentric 51 which causes the stop 49 to contact with the eye 54 which action will rock the bell crank lever 53 and cause said hooks to move as described. The 85 operation so far described, includes in detail every action which takes place upon a downward stroke and upward stroke of the piston or in other words, a full revolution of the crank shaft 2 and fly wheel F. 90 The operation of the crank 10' to actuate the piston 5 at proper intervals, is made possible by the correct proportioning of the gears 8 and 9, this proportion being 2:1. 95 From the foregoing description, taken in connection with the accompanying drawings, the construction and operation of the invention will be readily understood without requiring a more extended explanation. 100 It will be noted that the construction of the various parts is such that gas may be compressed upon every upward stroke of the piston 4 and that the downward strokes of said piston and the supplemental piston, not only imparts power to the crank but discharges all exhaust gases from the cylinder and simultaneously draws a fresh charge of gas into said cylinder to be compressed by the upstroke of said pistons, as previously set forth. 105 110 Although I have described my invention with considerable minuteness, I do not wish to be limited to details of construction other than those amplified in the appended claims. 115 Having thus described my invention, what I claim as new and desire to secure by Letters Patent is:

1. In an internal combustion engine a cylinder, a crank shaft, a power piston mounted for reciprocation within said cylinder and connected with said crank shaft, a supplemental piston within said cylinder between the head thereof and said power piston and means operated by said crank shaft for locking said supplemental piston against reciprocation until said power piston has neared the end of a working stroke, mechanism for then releasing said locking means, means for rapidly moving said supplemental piston toward said power piston to expel the burnt gases and to simultaneously draw 120 125 130

- in a fresh charge of gas between said supplemental piston and the cylinder head and for returning said supplemental piston at a speed more rapid than the return travel of said power piston, means for conducting the fresh charge of gas into the space between said power and supplemental pistons, and mechanism for releasing the operating means for said supplemental piston and for actuating the locking means therefor.
2. In an explosive engine, a cylinder, a crank shaft, a power piston mounted for reciprocation within said cylinder and connected to said crank shaft, a supplemental piston mounted for reciprocation within said cylinder, a clutch reciprocated by the crank shaft, means for alternately connecting said supplemental piston with said reciprocating clutch and for locking said piston against reciprocation.
3. In an explosive engine, a cylinder, a crank shaft, a power piston mounted for reciprocation within said cylinder, a supplemental piston mounted for reciprocation within said cylinder between the head thereof and said power piston, said head having an opening, a piston rod slideable through said opening and connected to said supplemental piston, a cross head slideable upon said piston rod and reciprocated by said crank shaft, shoulders on said piston rod, a hook on said cross head, a hook supported by said cylinder and means for simultaneously engaging one of said hooks with and for disengaging the other hook from said shoulders.
4. In an explosive engine, a cylinder, a crank shaft, a power piston mounted for reciprocation within said cylinder, a supplemental piston mounted for reciprocation within said cylinder between the head thereof and said power piston, said head having an opening, a piston rod slideable through said opening and connected to said supplemental piston, a cross head slideable upon said piston rod and reciprocated by said crank shaft, shoulders on said piston rod, a hook on said cross head, a hook supported by said cylinder, a bell crank lever pivotally supported by said cylinder and formed with an eye, an eccentric on the crank shaft, a rod reciprocated by said eccentric and passing loosely within said eye, shoulders on said rod and adapted to engage said eye and thereby rock said bell crank and connections between said hooks and said bell crank for simultaneously engaging one of said hooks with and disengaging the other
- hook from the shoulders on said piston rod, when said bell crank is rocked.
5. In an internal combustion engine, a main cylinder, a power and a supplemental piston mounted for reciprocation therein, a supplemental cylinder, vertically spaced ports establishing communication between said supplemental and main cylinders at a point directly inside the latter and at a point spaced outwardly therefrom, a plunger in said supplemental cylinder, a stem depending from the lower end of said plunger, a guide secured to and offset from said cylinder to slidably receive said stem, and a spring interposed between the plunger and said guide, said plunger acting to close the port disposed contiguous to the head of said main cylinder on an intake stroke of the supplemental piston and to automatically open said communication against the tension of its spring on a compression stroke of said supplemental piston substantially as and for the purpose set forth.
6. In an internal combustion engine, a main and a supplemental cylinder, vertically spaced ports communicating with the interiors thereof at a point directly within the head of said main cylinder at a point spaced outwardly therefrom, a power piston and a supplemental piston mounted for reciprocation within said main cylinder, said supplemental piston being located between said power piston and the head of said main cylinder, means for reciprocating said supplemental piston at predetermined intervals, a plunger within said supplemental cylinder, a stem depending from the lower end of said plunger, a guide secured to an offset from said main cylinder to slidably receive said stem, and a spring interposed between the plunger and guide to close the port disposed contiguous to the head of said main cylinder upon the outward movement of said supplemental piston, said movement drawing in a fresh charge of gas between said supplemental piston and the cylinder head, and expelling the burnt gases from the cylinder, said spring yielding on the return stroke of the supplemental piston substantially as and for the purpose set forth.

In testimony whereof I have hereunto set my hand in presence of two subscribing witnesses.

WALTER W. CONNERS.
